Patented Aug. 30, 1921.

UNITED STATES PATENT OFFICE.

ABRAHAM BRILLIANT, OF BOSTON, MASSACHUSETTS.

COMPOUND TOOL FOR WATCHMAKERS.

1,389,119.

Specification of Letters Patent. Patented Aug. 30, 1921.

Application filed May 6, 1921. Serial No. 467,334.

To all whom it may concern:

Be it known that I, ABRAHAM BRILLIANT, a citizen of Russia, residing at Boston, in the county of Suffolk and State of Massachusetts, have invented new and useful Improvements in Compound Tools for Watchmakers, of which the following is a specification.

This invention has for its object to provide 10 a compound tool of the pliers type, whereby a watch-maker or repairer may remove various component parts of a watch movement, said parts including the balance roller, the hands, the hair spring stud, and any of the 15 jewels, without liability of injury to any part, all the elements employed in performing said operations being contained in a single tool, so that the inconvenience of employing a plurality of independent tools is 20 avoided.

The invention is embodied in the improvements which I will now proceed to describe and claim.

Of the accompanying drawings forming 25 a part of this specification,

Figure 1 is a side view of a tool embodying the invention.

Figs. 1^a and 1^b are fragmentary side views, showing different adjustments.

30 Fig. 2 is a top view of a portion of the tool.

Figs. 3 and 4 are bottom views of a portion of the tool.

Fig. 5 is an enlarged perspective view of 35 one of the jaws, shown by Figs. 1, 3 and 4.

Fig. 6 is an enlarged side view of one of the posts shown by Figs. 1 and 2.

Fig. 7 is a section on line 7—7 of Fig. 6.

Fig. 8 is an enlarged side view of the other 40 post shown by Figs. 1 and 2.

Fig. 9 is a top view of a portion of the tool, illustrating the use of the tool in removing a roller.

Fig. 10 is an enlarged section on line 45 10—10 of Fig. 9.

Fig. 11 is a view similar to Fig. 9, illustrating the use of the tool in removing hands.

Fig. 12 is an enlarged section on line 50 12—12 of Fig. 11.

Fig. 13 is a view similar to Fig. 9, illustrating the use of the tool in removing a hair spring stud.

Fig. 14 is an enlarged section on line 14—14 of Fig. 13.

Fig. 15 is a top view of a portion of the 55 tool, illustrating the operation of removing a jewel.

Fig. 16 is an enlarged section on line 16—16 of Fig. 15.

Fig. 17 is a fragmentary side view showing 60 modifications.

The same reference characters indicate the same parts in all of the figures.

I connect by a pin or pivot 14, two crossed levers to form a tool of the pliers type, having relatively short operating arms 12 and 13, and longer arms 12^a and 13^a, forming handles. The arm 12 is shorter than the arm 13, and is provided with laterally projecting ears 15. Two jaws 16 are connected 65

with said ears by pivots 17, at right angles with the lever-connecting pivot 14, the jaws being adapted to swing toward and from each other in a plane at right angles to the path in which the arms 12 and 13 swing 70

toward and from each other. The jaws 16 are normally closed against each other, as shown by Fig. 3, by a spring 19, which is preferably a bent wire passed through a hole drilled through the pivot 14, and having hooked ends engaged with holes 20 in the jaws. Arms 21 formed on the jaws provide 75

means whereby the jaws may be opened, as shown by Fig. 4. Each jaw 16 has a reduced inner edge 22, abutting against a 80

similar edge on the other jaw when the jaws are closed, and a flat upper face 23, the upper faces of the two jaws collectively forming a seat for the roller 24 on a balance staff 25, as shown by Fig. 10, a seat for the 85

hub portion 26 of a watch hand 27, as shown by Fig. 12, a seat for the portion 28 of a balance cock which receives the hair spring stud 29, as shown by Fig. 14, and a seat for a bridge 30 containing a jewel 31, as shown 90

by Fig. 16, the bridge here shown being the bottom bridge containing a jewel which constitutes a bearing for the balance staff. The 95

jaw edges 22 are provided with notches 22^a, forming an orifice, adapted to receive the 100 arbor of the seconds hand of a watch when the jaws are closed, as shown by Fig. 3. The jaws are, therefore, adapted for use in removing the seconds hand by a prying action.

The longer operating arm 13 is provided with two post-receiving sockets 32 and 33 (Fig. 2), and with set screws 34, adapted to secure posts in said sockets. The socket 32 is nearer the pivot 14 than the socket 33, and the arrangement is such that the inner socket 32 is adapted to hold a post 35 coöperating with the jaws in removing a roller 24, and a hand 27. The socket 32 is 10 also adapted to hold a post 36 coöperating with the jaws in removing a jewel 31. Each post is adapted to be secured in either socket, the outer socket 33 being employed to hold the post 35 when the latter is used for removing a hair spring stud in a Swiss watch. The outer socket is also employed to hold either post which is not in use. This will be understood by reference to Figs. 1 and 1^a.

The post 35 is reversible and provided 20 with reduced end portions 35^a and 35^b. The portion 35^a is socketed to engage the balance staff 25 (Fig. 10), and the portion 35^b forms a pin, adapted to bear on a center wheel post 38 (Fig. 12), and on a hair spring stud 29 (Fig. 14). When the socketed portion 35^a is in use, the post 35 is secured in the inner socket 32, and when the pin portion 35^b is in use, the post 35 is secured in the outer socket 33, as shown by Fig. 1^b.

The post 36 is used only in removing a jewel 31. This post is partially divided to form 30 normally diverging spring fingers 36^a which are reduced to form an acting end of variable diameter, adapted to bear on a jewel, the diameter of the acting end depending on the size of the jewel. The post is provided with a movable collar 40, frictionally engaged with the fingers 36^a, and adapted to maintain the said acting end at the desired 40 diameter. When a relatively large jewel is to be removed, the collar 40 is raised, as shown by full lines in Fig. 8. Downward movement of the collar contracts the acting end, as indicated by dotted lines.

The operating arms 12 and 13 are normally forced apart by a spring 41, engaged 50 with the handle arms. The tool may be operated by placing the jaws in either of the positions shown by Figs. 10, 12, 14 and 16, while the arms 12 and 13 are spread apart, and then suitably decreasing the distance between said arms to cause the acting post to coöperate with the jaws in removing either a roller, the hour and minute hands, 55 a hair spring stud, or a jewel. The removal of the seconds hand may be accomplished by the jaws alone, without the coöperation of a post therewith.

Fig. 17 shows the arm 13 bent so that its 60 outer portion is more nearly parallel with the arm 12, when the arms are fully separated, than in the arrangement shown by Fig. 1, the bent form shown by Fig. 17 being preferable.

Fig. 17 also shows a modified construction

of the jewel-removing post 36, the post being slotted to form spring fingers 36^b, which are normally closed together, and may be separated by a screw 43 engaged with a tapped orifice in one finger and bearing on 70 the other finger, so that when the screw is turned inward, the fingers are forced apart.

I claim:

1. A watch-maker's tool comprising a pair 75 of crossed levers; a transverse pivot connecting said levers, each lever having an operating arm and a longer handle arm, one of said operating arms being shorter than the other, a pair of spring-closed jaws connected with the shorter operating arm by pivots at right angles with the lever-connecting pivot, and provided with means whereby they may be manually opened, the jaws having thin notched meeting portions 80 collectively forming a seat, adapted to bear on either a watch balance roller, a watch hand, a jewel holder, or a hair spring stud holder, the longer arm being provided with a post-receiving socket, and with means for detachably securing a post therein, and two 85 interchangeable posts; each adapted to be secured in said socket, and to coöperate as described, with said jaws, one post being formed to act in removing a roller, hands, and a hair spring stud, and the other post 90 being formed to act in removing a jewel, the tool being provided with means for holding either post in an inoperative position.

2. A watch-maker's tool comprising a pair 95 of crossed levers; a transverse pivot connecting said levers, each lever having an operating arm and a longer handle arm, one of said operating arms being shorter than the other, a pair of spring-closed jaws connected with the shorter operating arm by pivots at right 100 angles with the lever-connecting pivot, and provided with means whereby they may be manually opened, the jaws having thin notched meeting portions collectively forming a seat, adapted to bear on either a watch 105 balance roller, a watch hand, a jewel holder, or a hair spring stud holder, the longer arm being provided with two sockets at different distances from the lever-connecting pivot, and with set screws adapted to confine posts 110 in said sockets, and two posts, each insertible in either socket, one of said posts being adapted to coöperate with said jaws in removing a roller, a watch hand, and a hair 115 spring stud, and the other post being adapted to coöperate with the jaws in removing a jewel.

3. A watch-maker's tool substantially as specified by claim 1, one of said posts being reversible, and provided with reduced end 125 portions, one of which is socketed to engage a balance staff, the other constituting a pin, adapted to bear on a center staff and on a hair spring stud holder.

4. A watch-maker's tool substantially as 130

specified by claim 1, the jewel-removing post being partially divided to form normally diverging spring fingers forming an acting end of variable diameter, and provided with 10 a movable collar frictionally engaged with said fingers, and adapted to maintain the said acting end at the desired diameter.

5. A watch-maker's tool substantially as specified by claim 1, the jewel-removing post

being slotted to form spring fingers forming an acting end of variable diameter, and provided with means for maintaining said fingers at different distances apart to vary the diameter of said acting end.

In testimony whereof I have affixed my 15 signature.

ABRAHAM BRILLIANT.
